HOBBYHORSE

Hattie L. West, Shreveport, La.

Application November 7, 1950, Serial No. 12,868

Term of patent 14 years

(Cl. D34—15)

To all whom it may concern:

Be it known that I, Hattie L. West, a citizen of the United States, residing at Shreveport, in the parish of Caddo and State of Louisiana, have invented a new, original, and ornamental Design for a Hobby Horse, of which the following is a specification, reference being had to the accompanying drawing, forming part hereof.

The dominant features of the design are shown in full lines.

I claim:

The ornamental design for a hobby horse, as shown and described.

HATTIE L. WEST.
